UNITED STATES PATENT OFFICE.

ANTON KRIEGHOFF (NOW BY JUDICIAL CHANGE OF NAME ANTHONY WARFIELD),
OF CHELSEA, MASSACHUSETTS, ASSIGNOR, BY MESNE ASSIGNMENTS, TO CORA R.
NUNN, OF BOSTON, MASSACHUSETTS.

PIANO.

Application filed February 1, 1917, Serial No. 146,004. Renewed June 21, 1922. Serial No. 569,882.

To all whom it may concern:

Be it known that I, ANTON KRIEGHOFF (now by judicial change of name ANTHONY WARFIELD), a citizen of the United States, residing at 50 Nichols Street, Chelsea, county of Suffolk, State of Massachusetts, have invented an Improvement in Pianos, of which the following description, in connection with the accompanying drawing, is a specification, like characters on the drawing representing like parts.

This invention relates to an improved construction in stringed musical instruments and is more particularly directed to pianos. The novel construction herein disclosed is an improvement in structures along the lines of the advance in this art disclosed in the applications for Letters Patent heretofore filed by the inventor hereof, viz, Serial No. 27,927, filed May 13, 1915, Patent No. 1,261,406, granted April 2, 1918, and Serial No. 49,145, filed September 7, 1915, Patent No. 1,239,113 granted Sept. 4, 1917. The general purpose of these inventions is to produce a piano or similar instrument in which the resonant parts (particularly the sounding-board) are free to respond in the fullest manner consonant with that degree of structural strength necessary in the instrument to withstand the stresses set up by the strings. It is further proposed to augment the resonance of the instrument by the use of the hitch plate which is separate and distinct from the frame, which is supported from the wrest plate at one side and so connected to the sounding board as to vibrate in consonance with the latter.

The present novel construction broadly comprises the customary frame of wood; a sounding-board supported thereby at its edges; a rigid metallic wrest plate secured to the wooden frame or to the usual wrest plank; and the provision of a flexible metallic hitch plate, which is adapted to vibrate. The common integrally cast metal string plate is only slightly vibratory and is designed chiefly to provide strength and rigidity to resist the stresses set up by the combined tension of the strings. This novel vibratile hitch plate is a separate entity and is provided with an improved resilient support. It is supported by the wrest plate and otherwise is only connected yieldably to the frame and its supporting means are wholly out of contact with the sounding-board. The

strings are attached to wrest pins on the wrest plate which is rigid and is secured to the frame. Hitch pins and bridges for the strings are provided on the vibratile hitch plate. Suitable struts brace the vibratile hitch plate against the stresses of the strings. The hitch plate is preferably made light in weight and of such degree of flexibility that it may vibrate freely substantially throughout its area. The struts are so mounted and disposed as to afford efficient bracing and to permit free vibration of the hitch plate. The bridges afford means for communicating the vibrations of the strings to the vibratile hitch-plate and sound-posts or transmitters communicate these vibrations to the sounding-board.

The object of the invention is to produce an improved piano construction.

A more specific object is to augment the resonance of the instrument by omitting the usual sounding-board bridges, and by using a separate vibratile hitch plate having a rib or ribs for supporting the strings instead of the usual sounding-board bridges.

Other objects of the invention will more fully appear from the following description and the accompanying drawings and will be pointed out in the annexed claims.

In the accompanying drawings, there has been disclosed a structure designed to carry out the objects of the invention, but it is to be understood that the invention is not confined to the exact features shown as various changes may be made within its reasonable scope.

Fig. 1 is a plan view of the assembled vibratile member and sounding-board;

Fig. 2 is a section on the line 2—2 of Fig. 1;

Fig. 3 is a section through one of the resilient supports;

Fig. 4 is a sectional view of one of the transmitters;

Fig. 5 is a view showing the mounting of one of the braces on the wrest plate.

The drawings of this application disclose a selected embodiment of this invention as applied to a piano of the grand type although obviously with slight changes it may be incorporated in pianos of the upright type and in other similar instruments of various types.

The sounding-board 1 is supported at its edges in the usual manner by a portion of

the wooden frame 2-3. The piano casing and frame supports are not involved in this invention and are not therefore shown or described. A wrest plank 3 is provided, as is usual, but its upper surface is covered preferably by a series of laminations 4 of wood or other suitable material. The wrest plate 5 is superposed upon the top layer and is secured to the laminations and the wrest 50 plank in any suitable manner. The wrest plate 5 is of novel construction so as to afford supporting and bracing means for the vibratile hitch-plate.

The vibratile hitch plate 6 is preferably 15 made of a metal which affords that requisite degree of flexibility which will give rise to the desired degree of vibratility. Herein, this vibratile hitch-plate is shown apertured or cut away, thus effectively reducing the 20 weight of the plate and eliminating surplus metal. This light plate is provided with a resilient mounting. The elongated form of this plate may be roughly considered for descriptive purposes as that of a triangle 25 with a narrow curved base 7 and long curved sides. The base of the triangle forms the bass portion 7 of the plate and bears the hitch pins 8 and a rib or bridge 9 for the bass strings 10; while the longer side, which 30 may be designated as the inner side, bears marginal hitch pins 11 and a plurality of short ribs 13 each of which is formed to serve as a bridge for a single series of treble strings known as a unison. These little 35 separate bridges are so positioned that each bridge is transverse to the length of the string or strings engaged. These bridges 13 are, in this embodiment, provided only for the treble strings 12, although, obviously, 40 they may be also provided for the bass strings which are here shown as engaging the rib 9 which is cast integrally with the plate and extends substantially across the base thereof.

45 The opposite end of the elongated vibratile hitch-plate 6, which may be considered as the treble end 14 of the plate, is provided with a novel pivotal mounting or support. A raised shoulder 15 is integral- 50 ly cast on the plate and has formed therein a recess 16 which receives one end portion of the cylindrical rod 17. This rod has its opposite end portion held within a recess 18 in a portion of the rigid wrest plate 5 55 secured to the frame 2. The vibratile plate is thus pivotally connected to the wrest plate at one end. The bass portion 7 of the plate 6 is preferably supported by the frame in a yieldable manner 60 and out of contact with the sounding-board 2. This is done in order that the vibratility of the plate 6 may not be greatly impaired by rigid supports at this end and that the vibratility of the sounding-board may not 65 be impaired by the contact of the supporting

means. In the preferred embodiment illustrated herein posts 19 are provided which are of a length sufficient to extend from a point above the hitch-plate 6, through the hitch plate, and sounding-board and are 70 anchored in the frame. The post structures, two being here shown, are similar and but one is necessary to be described. A washer 20 and nut 21 are held in threaded engagement about the end portion of the post 75 while a washer 22 is placed about the post where it emerges from the frame aperture.

A coiled spring 23, encircles the post, one end bearing upon the washer 22, as shown in 80 Fig. 3. The portion of the plate 6, adjacent its post aperture rests upon the upper end portion of the spring 23. A second coiled spring 24, encircles the post 19 85 and its lower end bears upon the upper face 85 of the plate adjacent its post aperture. The upper end of this spring 24 is held by a washer 25 and nut 26, the latter being held in threaded engagement with the end portion of the post. The plate 6, therefore, 90 through the two similar post supports is yieldably held in position. The apertures 27 in the sounding board 1 are of such diameter that the lower springs 23 may unrestrictedly pass therethrough out of contact therewith.

The strings, both the treble 12 and the bass 10, have wrest pins 28, bridges 29, and pressure bars 30 on the wrest plate 5. It is therefore obviously essential that the plate 6 be braced in order to withstand the stresses set up by the strings. And, while any suitable bracing means may be employed, it is preferred in this embodiment to use a plurality of bracing struts positioned to abut 105 against the wrest plate and the flexible vibratile hitch plate. In the structure here disclosed, three such braces are used. For convenience of indication they may be designated as the bass brace 31, the middle brace 110 32 and the treble brace 33. The brace 31 is substantially positioned in parallelism with the lowest bass strings; the brace 32, with the highest of the bass strings; and the brace 33, with the treble strings. These braces are 115 desirably formed of T-iron the braces 32 and 33 being in a position corresponding to the normal upright position of the letter T, while the bass brace 31 has a relatively inverted position. The middle brace 32 is 120 mounted as shown in Fig. 2, wherein the brace at the outer end abuts against a lug 34 which is preferably cast integrally with the hitch-plate and is a continuation of the rib 9 which supports the bass strings 10. This lug 34 is angularly disposed with relation to the bridge 9 in order to be presented substantially transversely to the longitudinal axis of the brace 32. The brace 32 is 125 here shown as having its outer end portion 130

- 35 offset so that the brace is maintained out of contact with the strings. The corresponding outer end of the treble brace 33 is similarly mounted. In practice it has been 5 found desirable to shape the terminal face of the brace so that the edge 36 (see Fig. 2) slopes backwardly and upwardly toward the top of the T-iron, the top end portion overlapping the upper face of the lug 34. 10 The side 37 of the lug 34 which engages this brace edge 36 is reversely sloped as shown in Fig. 2. Hence, the brace is held against any liability to upward displacement. The corresponding end of the treble 15 brace is similarly mounted. A lug 38, angularly offset as is the lug 34, serves as the support for the outer end of the bass brace 31. This brace, being inverted, has an engagement with the lug 38 which is invertedly similar to the middle brace and is 20 therefore not necessary to be shown or described. The struts or braces by being thus positioned to engage at their ends respectively the wrest plate and the rib upon the 25 vibratile member or string plate are adapted to resist the entire tension of the strings and to permit said vibratile member or string plate to move freely toward and from the sounding board in its vibratile movement. Inasmuch as the vibration of the 30 string plate toward and from the sounding board extends through a practically negligible arc there is no variation in the tension upon the strings which will interfere with 35 the amplitude or quality of their tonal vibration.
- The inner ends of all the braces are mounted against the rigid wrest plate 5. The novel wrest plate 5 is preferably formed in 40 one integral casting. This casting is formed with a plurality of projecting webs or fins which support and reinforce the bar 39 against which the three braces abut and are supported. This bar 39 is formed so that 45 its under surface is above the plane of the wrest plate surface and permits all strings to pass under the bar and out of contact therewith to the inner bridges 28. The juncture of the inner end of the middle 50 brace 32 and the bar 39 is shown in Fig. 5 wherein the T-iron 32 has the end face of its upright portion abutting against a lug 40 which is preferably integrally formed on the bar 39. The outer face of this lug 40 is sloped upwardly and outwardly, as 55 shown, while the adjacent face of the upright portion of the T-iron brace 32 is symmetrically formed to fit closely thereagainst. The flat top portion projects 60 slightly to overlap the upper face of the lug 40. The inner end of the brace 33 is similarly supported. This inclined abutment, like the inclined engagement of the outer ends of the braces heretofore mentioned, serves to prevent upward displace- 65
- ment of the braces. The inner end of the bass brace 31 abuts against its lug 40 and is mounted similarly to the mounting of its opposite end against the lug 38 above referred to. The wrest plate is provided with 70 a plurality of strengthening members comprising an upwardly projecting flange 41 preferably formed upon the wrest plate casting along its three sides—those other than the inner or bar side. The flange portions of the two short sides adequately strengthen the wrest plate against the thrust of the bass brace and the mounting of the treble end of the vibratile flexible plate 6. A short web 42 similarly serves 80 the bar 39 opposite the mounting of the inner end of the treble brace 33 while a web 43 joining the bar 39 and the flange 41 strengthens the mounting of the inner end of the brace 32. 85
- The vibratile hitch plate is thus adapted to vibrate freely throughout its area and readily responds to the vibrations of all of the strings which, as shown and described, have bridges on this vibratile plate. 90 Means are afforded whereby the vibrations of the flexible hitch-plate may be fully and efficiently communicated to the sounding-board. To this end there are provided a plurality of transmitters, shown in Fig. 4. 95 These transmitters each consist of a post 44, preferably of metal, which is connected to the vibratile hitch-plate 6 and is received in threaded engagement in the wooden sounding-board. In this disclosure, a block 100 of wood 45 is affixed to the under face of the sounding-board opposite each post and receives in threaded engagement the post end which projects through the sounding-board. The other end of the post extending 105 through the vibratile hitch-plate 6, has threaded thereon two nuts 46 which are turned tightly against the upper and under faces respectively of the vibratile hitch-plate. These transmitters may be disposed 110 in any suitable manner and in any desired number efficiently to accomplish their function of transmitting the vibration of the vibratile hitch-plate 6 to the sounding-board. In Fig. 1 is disclosed the disposition of a number of these transmitters. 115
- This invention has produced a novel piano construction in which the usual rigid string plate is eliminated. The usual string plate is stiff and heavy to attain the strength 120 requisite to withstand the enormous aggregate tensions of the strings and its vibratility is of slight value. Further, such string plates are secured to the outer and non-vibratory portions of the sounding-board. 125 Hence, the string-plate is itself but slightly vibratory and its vibrations can only be transmitted to the non-vibratory margins of the sounding-board. In the new structure, the vibratile plate is relatively light and 130

flexible as compared to the usual string plate. It is mounted in a yieldable manner out of contact with the freely vibratory sounding-board except through the sound transmitters 5 so disposed as to communicate efficiently its vibratory energy to the sounding-board.

While there has been illustrated herein a selected embodiment of the invention, it is to be understood that the construction disclosed is illustrative but not restrictive and that the same may be modified within the meaning and scope of the claims which follow.

Having fully described my invention, 15 what I claim as new and desire to secure by Letters Patent is:

1. A musical instrument comprising a frame, a sounding-board and strings, a vibratile hitch plate separate from said frame, means for pivotally supporting the latter to permit bodily vibration thereof in consonance with the sounding-board.

2. A musical instrument comprising a frame, strings and sounding-board, a vibratile hitch plate separate from the frame, means for connecting the strings to said hitch plate, means for supporting said hitch plate against the tension of the strings, but adapted to permit the hitch plate to vibrate bodily, and means for transmitting the vibration of said hitch plate to the sounding board.

3. A musical instrument comprising a frame, a sounding-board, a wrest plate, a vibratile hitch plate separate from the frame, strings connected to said hitch plate and said wrest plate, means pivotally connecting one end of said hitch plate to said wrest plate, and a plurality of struts engaging said vibratile hitch plate and said wrest plate and acting to brace said hitch plate against the action of the strings, whereby the hitch plate is prevented from yielding relatively to the wrest plate under the tension of the strings, but is permitted to vibrate freely in consonance with the sounding-board.

4. A musical instrument comprising a frame, sounding-board and wrest plate, a vibratile hitch plate, strings connected to said hitch plate and said wrest plate, means pivotally connecting one end of said hitch plate to said wrest plate, and a plurality of struts engaging the edge of said vibratile hitch plate and said wrest plate and acting to brace said hitch plate against the action of said strings, whereby said hitch plate is prevented from yielding relatively to the wrest plate under the tension of the strings, but

is permitted to effect free transverse vibrations, and resilient means sustaining the hitch plate in a predetermined position relatively to the sounding-board. 60

5. A musical instrument comprising a frame, strings and sounding-board, a wrest plate secured to the frame, a free vibratile hitch plate separate from the frame, means including a plurality of struts engaging said vibratile hitch plate and said wrest plate and operating to support said hitch plate, a plurality of bridges on said vibratile hitch plate, each of said bridges being substantially normal with the direction of the strings supported by them, and means for communicating to the sounding-board vibrations of 75 said hitch plate.

6. A musical instrument comprising a frame, strings, and sounding-board having apertures therein, a wrest plate secured to the frame, an elongated vibratile hitch plate 80 separate from the frame, means for supporting said vibratile hitch plate from said wrest plate, a plurality of posts secured to the frame, each projecting through the apertures in the sounding-board and the vibratile hitch plate, a spring coiled about each post and compressively held by the under face of the hitch plate and the top face of the frame, the sounding-board apertures being of a diameter larger than that of the 85 diameter of the springs, a retaining member on the upper end of each post, a second spring coiled about each post and compressively held between the top face of the hitch plate and said retaining member, whereby 90 the vibratile hitch plate is resiliently supported, means for communicating the spring vibrations to the hitch plate, and means for communicating the vibrations of the hitch plate to the sounding-board. 95

7. A musical instrument comprising a frame, strings, a sounding-board, a wrest plate, a triangular shaped hitch plate separate from said frame, pivotally connected adjacent its apex to the wrest plate, a plurality of struts engaging said hitch plate and said wrest plate acting to brace such hitch plate against the tension of the said strings, means for communicating the vibrations of the strings to the hitch plate, 105 and means for communicating the vibrations to the sounding-board. 110

In testimony whereof, I have signed my name to this specification.

ANTON KRIEGHOFF.

Now by judicial change

ANTHONY WARFIELD.
